EXPANSIBLE ROTARY DRILL BIT

Archer W. Kammerer, Fullerton, Calif.

Application February 9, 1951, Serial No. 210,139

9 Claims. (Cl. 255—76)

1

This invention relates to drill bits, and more particularly to drill bits of the expandable type for drilling or reaming holes below well casing greater in diameter than the inside diameter of the casing through which the bit is capable of passing.

An object of the present invention is to provide an improved retaining device for maintaining a mandrel in appropriate telescopic relation within the main body of an expandable rotary drill bit.

Another object of the invention is to provide a retaining device for maintaining a mandrel in appropriate telescopic relation within the main body of an expandable rotary drill bit, which device enables the mandrel to be assembled and disassembled with respect to the bit body at a substantial savings in time and at a greatly reduced cost.

A further object of the invention is to provide a retaining device in a drill bit of the aforesaid character that is capable of transmitting safely high loads between the mandrel and the bit body.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a longitudinal section through a drill bit, with parts shown in retracted position for lowering through the well bore;

Fig. 2 is an enlarged cross-section taken along the line 2—2 on Fig. 1;

Fig. 3 is a fragmentary longitudinal section, on an enlarged scale, through the mandrel locking portion of the drill bit;

Fig. 4 is a cross-section taken along the line 4—4 on Fig. 1.

The rotary drill bit A disclosed in the drawings is of the general type disclosed in United States Patent No. 2,466,991. It is attachable to a string of drill pipe B for lowering through a well casing C in a well bore D to a point below the casing shoe E at which enlargement of the well bore is to commence. The drill bit may have a pilot bit 10 at its lower end for centering the tool in hole that may have already been drilled, or for drilling the central portion of new hole,

2

in the absence of a pre-existing hole. The main portion of the bit is capable of enlarging the bore hole by producing and operating upon a formation shoulder (not shown), as fully described in the above referred to patent.

The upper end of the bit consists of a driving mandrel 11 having an upper pin 12 threadedly connected to a sub 13 forming the lower end of the string of drill pipe B. This mandrel includes an upper kelly or drill stem member 14 telescoped within and slidably splined to the main body 15 of the bit. As disclosed in the drawings, the slideable splined arrangement may be provided by forming the exterior 14a of the kelly hexagonal in shape, and having such portion of the kelly telescopically received in a companion hexagonal socket 15a within the body 15, disposed below a counterbore 16 in the body extending to its upper end.

20 The mandrel 11 has a limited range of longitudinal movement within the body 15, its upward movement being limited by engagement of an external shoulder 17 on the kelly, positioned within the counterbore 16, with a retaining ring or sleeve 18 disposed within the counterbore 16 and releasably secured to the body 15, in a manner hereinafter described.

25 The body 15 has a plurality of expandable parts mounted upon it, comprising cutter supporting members 19 pivotally mounted in a body slot 20 on pivot or hinge pins 21 suitably secured to the body. Each cutter supporting member 19 consists of a depending leg 22, having a bearing supporting pin 23 inclined inwardly and downwardly, and on which a roller side cutter 24 is mounted through the agency of roller and ball bearing elements 25, 26 that may be disposed between the bearing pin 23 and cutter 24 in any suitable manner. Each

30 cutter supporting member also includes an upwardly extending arm 27 against which an elastic expander 28 bears. This expander is in the form of a compressed helical spring received within a socket 29 in the body and exerting its force against the arm 27; so as to tend to swing it inwardly and thus urge the cutter 24, on the other side of the fulcrum pin 21, in an outward direction. The extent of such outward movement may be limited by engagement of stop shoulders 30 on opposite sides of the cutter supporting members 19 with cooperable body stop shoulders 31.

35 After the cutters 24 have been expanded outwardly by the expander springs 28 to the maximum extent, they can be locked in this position by a tubular member 32 of the mandrel 11, which

is piloted in the kelly 14 and suitably secured thereto against relative longitudinal movement by a lower shoulder 33 abutting a companion shoulder 34 on the kelly and an upper nut 35 threaded on the upper end of the tubular member 32 and bearing upon an upper shoulder 36 on the kelly. The tubular member 32 is provided with a lock portion 37 that can be moved from an upper position in transverse alignment with inner supporting member recesses 38, which allow the cutters 24 to be retracted, to a lower position opposite lugs 39 formed on and projecting inwardly from the supporting member legs 22, which prevent retraction of the cutters, as explained in the patent above referred to.

The mandrel 11 is normally held in its upper position with respect to the main body 15 of the bit and supporting members 19 by a helical retractor spring 40 encircling the tubular member 32, with its upper end engaging the mandrel shoulder or flange 33 and its lower end engaging a spring seat and guide 41 at the lower end of the hexagonal body socket 15a. This spring seat 41 also serves as an upper bearing guide for the tubular member 32.

Circulating fluid can pass downwardly through the string of drill pipe B and through the tubular mandrel 32 for ejection from its lower discharge nozzle 42 onto the cutters 24, to cleanse them of cuttings and flush the latter from the drilling area to the top of the well bore. This circulating fluid is also availed of to unlatch the cutter supporting members 19, which may be held initially in retracted position in a positive manner.

The device for securing the cutter supporting members 19 positively in retracted position includes a hook 43 secured to the inner portion of each member 19, the ends of which are received in holes 44 in a strip 45 extending across the mandrel outlet 42. The drill bit, after having been lowered in retracted position to the point at which the reaming operation is to begin, may be released for operation by starting the pumps at the surface of the well bore, which will force fluid down through the drill string B and mandrel 32, causing it to impinge upon the latch strip 45, blowing or forcing the latter off the ends of the hooks 43, to permit the spring expanders 28 to shift the cutter supporting arms 27 inwardly and the cutters 24 outwardly against the formation.

In the operation of the device, the drill bit A is mounted on the lower end of the drill string B, with its parts held in retracted position by the latch strip 45. The mandrel 11 then occupies an upper position, illustrated in Fig. 1, in which the Kelly shoulder 17 is adjacent the retainer sleeve 18, and with the lock portion 37 elevated above the lugs 39 on the cutter supporting members 19, being received within the inner recesses 38 in the latter. The tool is lowered through the well casing C, and, upon reaching the position in the well bore below the casing shoe E at which the drilling operation is to begin, the pumps are started at the top of the well bore, causing fluid to impinge on the latch strip 45, forcing it hydraulically off the hooks 43 and releasing the cutter supporting members 19 for outward expansion under the influence of the springs 28.

The drill string B is then rotated, to rotate the main bit body 15 through the splined kelly and body connection 14a, 15a, the expander springs 28 forcing the arms 27 inwardly and the cutters 24 outwardly against the formation. Rotation is continued, without moving the drill string B

longitudinally, until the side cutters 24 enlarge the diameter of the hole to the maximum extent, as determined by the eventual abutting of the supporting member stop shoulders 39 with the companion body stop shoulders 31. When such abutting occurs, a formation shoulder will have been formed in the well bore D upon which the cutters 24 can rest, in order to support the latter and the body 15 and resist their downward movement.

Inasmuch as the body 15 cannot move downwardly, drilling weight imposed on the drilling string B shifts its connected mandrel 11 downwardly within the body against the action of the retractor spring 40 until the lower end of the kelly 14 engages the spring seat and guide 41. During this downward movement, the Kelly shoulder 17 is free to move downwardly within the body counterbore 16 away from the retaining sleeve 18. Such downward movement also shifts the tubular member 32 downwardly to position the lock portion 37 opposite and in alignment with the supporting member lugs 39, providing a positive lock that prevents inward movement of the cutters 24. So long as down weight is imposed on the drill string B, and the cutters 24 rest on the formation shoulder, the cutters are prevented from moving inwardly by engagement of their lugs 39 with the mandrel lock portion 37, which precludes the drilling of an undergauged hole.

Drilling is continued by rotating the drill bit A to ream the hole D in a downward direction to the desired extent. When the drill bit is to be retracted and removed to the top of the well bore, the drill string B is elevated, which moves the side cutters 24 above the formation shoulder and permits the retractor spring 40 to shift the body 15 downwardly to the extent determined by engagement of the retainer sleeve 18 with the external Kelly shoulder 17. This action repositions the mandrel lock portion 37 opposite the supporting member recesses 38 and above their lugs 39, allowing the cutters 24 and their supporting members 19 to swing inwardly when the tool passes back into the casing C upon elevation of the drill string B. The cutters and their supporting members will ride the wall of the casing during elevation of the string until the tool is removed from the top of the well bore. The force required to elevate the tool is transmitted in an upward direction from the Kelly shoulder 17 to the retaining ring or sleeve 18, and from the latter to the body 15 of the tool, through a retaining sleeve lock device now to be described.

The retaining sleeve 18 is piloted within the upper end of the main body 15 of the bit and has an external toroidal race 47 disposed opposite a companion toroidal race 48 in the bit body. Locking balls 49 are disposed circumferentially around the sleeve 18 and body 15, each ball being engageable with each race 47, 48. These balls are insertable between the races, and are removable therefrom, through a transverse hole 50 in the body extending into the body race 48. Removal of the balls 49 from the races 47, 48 may be prevented by a suitable plug 51 threaded into the hole 50. Inadvertent unscrewing of the plug 51 may be prevented in any suitable manner, as by producing indentations in the periphery of the plug 51 and adjacent body by a center punch.

The retaining sleeve 18 has its lower end spaced from the bottom of the counterbore 16 a sufficient extent to allow the mandrel 11 to move longitudinally with respect to the main body 15 of

the bit, for the purpose of appropriately positioning the lock portion 37 of the mandrel either above the supporting member lugs 39 or in alignment therewith, as described above. The sleeve 18 is disposed above the Kelly shoulder 17, its lower end being engageable by the latter. Upward thrust is transmitted from the shoulder 17 to the sleeve 18, and from the lower portion of the sleeve race 47 through the balls 49 to the upper portion of the body race 48. Inasmuch as a large number of balls 49 can be disposed circumferentially in the races 47, 48, their combined load transmitting capacity is very great, being greater than the maximum force to which the drill stem B and the drill bit A may be subjected. Should the drill bit become stuck in the hole, and it becomes necessary to jar upwardly upon it, the load carrying capacity of the sleeve 18 and intervening balls 49 is more than ample to transmit safely the maximum jarring force that might be required. When the mandrel 11 is disposed in a downward position within the main body 15 of the bit, as during the performance of a hole enlarging operation, there is no material force imposed on the sleeve 18. However, the balls 49 still prevent the sleeve 18 from dropping downwardly within the body 15, retaining it in its appropriate assembled position within the latter.

The sleeve and ball arrangement facilitates assembly and disassembly of the driving mandrel 11 within the bit body 15. Thus, with the sleeve 18 and balls 49 removed, the driving mandrel 11 is telescoped within the body; whereupon, the sleeve 18 may be slipped over the upper end of the kelly 14 and above the flange 17 of the latter, being inserted in the upper end of the kit body counterbore 16 until the sleeve race 47 is opposite the body race 48. The required number of balls 49 may now be placed through the body hole 50 and in the races; whereupon, the plug 51 is threaded into the hole, to prevent the balls 49 from leaving the races 47, 48. As mentioned above, a center punch may be used to form a metallic lock between the plug 51 and body 15 by deforming the outer margin of the plug.

The mandrel 11 is now held in appropriate position within the main body 15 of the bit, the sleeve and ball lock 47, 48, 49 preventing its removal from the latter. In addition, the sleeve and ball lock are capable of transmitting exceedingly high loads between the mandrel 11 and the body 15 of the tool. After the hole enlarging operation has been completed and the tool removed to the top of the well bore, the insertion of a suitable wrench (not shown) in a non-circular socket 51a in the screw plug 51 will allow the latter to be unthreaded from the hole 50; whereupon, the balls 49 can be removed through the open hole, the sleeve 18 slipped off the upper pin end of the driving mandrel 11, and the latter removed from the main body of the bit. The parts may be reassembled again, when desired, by re-telescoping the mandrel 11 in the body 15, placing the retaining sleeve or ring 18 over the kelly 14 and in the counterbore 16, reinserting the balls 49 through the body hole 50, and closing the latter with the plug 51. It is evident that all of the locking parts 18, 49, 51 can be used repeatedly, since there is no material wear on the latter. It is also evident that the assembly of the mandrel 11 in the body 15, and its disassembly therefrom, can be effected very easily and in a minimum of time.

The inventor claims:

1. In an expandible rotary well drilling bit: a main body; cutter means mounted on said body for lateral outward movement with respect to said body; means for expanding and holding said cutter means laterally outwardly of said body, said expanding and holding means including a mandrel telescoped and movable longitudinally within said body; an annular member piloted in said body to prevent withdrawal of said mandrel from said body; and rollable elements engageable with said annular member and body to prevent removal of said annular member from said body.
2. In an expandible rotary well drilling bit: a main body; cutter means mounted on said body for lateral outward movement with respect to said body; means for expanding and holding said cutter means laterally outwardly of said body, said expanding and holding means including a mandrel telescoped and movable longitudinally within said body; a sleeve disposed around said mandrel and piloted in said body to prevent withdrawal of said mandrel from said body; said sleeve and body having opposed races; and rollable elements on said races to prevent relative longitudinal movement in at least one direction between said sleeve and body.
3. In an expandible rotary well drilling bit: a main body; cutter means mounted on said body for lateral outward movement with respect to said body; means for expanding and holding said cutter means laterally outwardly of said body, said expanding and holding means including a mandrel telescoped and movable longitudinally within said body; a sleeve disposed around said mandrel and piloted in said body to prevent withdrawal of said mandrel from said body; said sleeve and body having opposed toroidal races; and balls in said races to prevent relative longitudinal movement in at least one direction between said sleeve and body.
4. In an expandible rotary well drilling bit: a main body; cutter means mounted on said body for lateral outward movement with respect to said body; means for expanding and holding said cutter means laterally outwardly of said body, said expanding and holding means including a mandrel telescoped and movable longitudinally within said body; an annular member engageable with said mandrel to prevent withdrawal of said mandrel from said body; said annular member and body being telescoped one within the other; and rollable elements engageable with said annular member and body to prevent removal of said annular member from said body.
5. In an expandible rotary well drilling bit: a main body; cutter means mounted on said body for lateral outward movement with respect to said body; means for expanding and holding said cutter means laterally outwardly of said body, said expanding and holding means including a mandrel telescoped and movable longitudinally within said body; a sleeve disposed around said mandrel and engageable with said mandrel to prevent withdrawal of said mandrel from said body; said sleeve and body being telescoped one within the other; said sleeve and body having opposed races; and rollable elements in said races to prevent relative longitudinal movement in at least one direction between said sleeve and body.
6. In an expandible rotary well drilling bit: a main body; cutter means mounted on said body for lateral outward movement with respect to said body; means for expanding and holding said

cutter means laterally outwardly of said body, said expanding and holding means including a mandrel telescoped and movable longitudinally within said body; a sleeve disposed around said mandrel and engageable with said mandrel to prevent withdrawal of said mandrel from said body; said sleeve and body being telescoped one within the other; said sleeve and body having opposed toroidal races; and balls in said races to prevent longitudinal movement in at least one direction between said sleeve and body.

7. In an expandable rotary well drilling bit: a main body; cutter means mounted on said body for lateral outward movement with respect to said body; means for expanding and holding said cutter means laterally outwardly of said body, said expanding and holding means including a mandrel telescoped within and slidably splined to said body, said mandrel having means thereon adapted for connection to a drill string to move said mandrel longitudinally in said body, said mandrel having a flange disposed in said body; a sleeve disposed around said mandrel and piloted in said body above said flange to limit upward movement of said mandrel relative to said body; and rollable elements engageable with said sleeve and body to prevent removal of said sleeve from said body.

8. In an expandable rotary well drilling bit: a main body; cutter means mounted on said body for lateral outward movement with respect to said body; means for expanding and holding said cutter means laterally outwardly of said body, said expanding and holding means including a

mandrel telescoped within and slidably splined to said body, said mandrel having means thereon adapted for connection to a drill string to move said mandrel longitudinally in said body, said mandrel having a flange disposed in said body; a sleeve disposed around said mandrel and piloted in said body above said flange to limit upward movement of said mandrel relative to said body; said sleeve and body having opposed toroidal races; and balls in said races to prevent relative longitudinal movement in at least one direction between said sleeve and body.

9. In an expandable rotary well drilling bit: a main body; cutter means mounted on said body for lateral outward movement with respect to said body; means for expanding and holding said cutter means laterally outwardly of said body, said expanding and holding means including a mandrel telescoped within and slidably splined to said body, said mandrel having means thereon adapted for connection to a drill string to move said mandrel longitudinally in said body, said mandrel having a flange disposed in said body; a sleeve above said flange and disposed around said mandrel to limit upward movement of said mandrel relative to said body; said sleeve and body being piloted one within the other; and rollable elements engageable with said sleeve and body to prevent removal of said sleeve from said body.
